COLLAPSIBLE TAP

Frederic Nell, Waynesboro, Pa., assignor to Landis Machine Company, Waynesboro, Pa., a corporation of Pennsylvania

Application February 7, 1934, Serial No. 710,171

11 Claims. (Cl. 10—145)

This invention relates to collapsible taps such as are used for cutting screw threads in holes, in pipe, tubes, etc. and its object is to provide a collapsible tap having improved means for collapsing the thread cutting elements and improved means for restoring the thread cutting elements to operative or thread cutting position.

A further object is to provide an improved collapsible tap of the character disclosed having a removable head.

A still further object is to provide improved means for locking the tap in thread cutting position and improved means for unlocking the locking means.

Further objects and advantages will become apparent as the description proceeds.

Referring to the accompanying drawings which are made a part hereof and on which similar reference characters indicate similar parts,

Figure 1 is a section on line 1—1 of Figure 3 showing the thread cutting elements in expanded or thread cutting position,

Figure 2, a longitudinal section, the same as Figure 1, showing the tap in collapsed or non-threading position,

Figure 3 is a face view of the tap,

Figure 4, a fragmentary sectional view on an enlarged scale of means for positioning the thread cutting elements in operating or thread cutting position,

Figure 5, a section on line 5—5 of Figure 3 showing one of the collapsing springs, and

Figure 6, a section on line 6—6 of Figure 3 showing the expanding or set-up spring.

In the drawings reference character 10 indicates a stock or body portion to which heads 11 of various sizes may be attached as by means of screws 15. The head 11 carries thread cutting elements 12 radially slidable in slots therein.

The inner edges of the cutters 12 engage surfaces 16 on a plunger head 13. The cutters 12 are provided with grooves 14 which grooves are engaged by tongues 19 on the plunger head. A solid key 17 on the head 11 engages a slot in the forward end of the body portion 10. The plunger head 13 is secured by means of an adjusting pin 20 to the plunger 18. The pin 20 serves to adjust the head 13 relative to the plunger 18. The axial position of the head 13 determines the radial position of the thread cutting elements.

It will be apparent that when the head is in its outermost position the threading elements will be in their outmost radial or thread cutting position and that when the plunger is retracted the thread cutting elements are drawn inward radially to

move them out of engagement with the work whereby the tap may be freely withdrawn from the work. The adjustable pin 20 has an enlarged end which engages a socket in the forward end of the plunger 18. A locking element 21 has a serrated forward end which engages the serrated end of the adjustable pin 20. A spring 22 surrounding the locking element urges it into engagement with the enlarged end of the adjusting pin 20. The locking element 21 is prevented from turning by a pin 40. The adjusting pin 20 preferably has a polygonal socket 41 in which a corresponding wrench may be seated for rotating the adjusting pin to adjust the head 13 axially. Due to the serrations on the end of the pin 20 and 15 the cooperating locking pin 21, the pin 20 is held in locked axial position so that jarring vibrations cannot change the radial position of the thread cutting elements 12. The plunger 18 is locked in forward position by means of a latch 23 shown 20 in Figure 1. This latch is pivotally mounted on a pin 24 on the body portion 10. The plunger 18 is cut out to receive a suitably hardened plate 25 against which an arm of the latch 23 engages to hold the plunger in forward position. The 25 plunger is held in its forward position by engagement of a surface 31 on the latch 23 with the surface 38 on the plate 25. A latch controlling ring or collar 26 is mounted on the body member 10. This collar has ears or lugs 27 in which are secured 30 holding rods 29 by means of bolts or screws 28. The rods 29 are secured at their forward ends in a ring 30 which ring is engaged by the work for moving the collar 26 rearwardly of the body portion. The rods 29 and ring 30 may be clamped 35 to the collar 26 in various positions depending upon the length of the thread desired, one extreme adjustment of the ring 30 being indicated in dotted lines in Fig. 1. A latch rack 31 is secured in the collar 26 by screws 39. This rack has 40 teeth engageable with teeth on the latch 23. Springs 32 shown in Figure 6 and springs 34 shown in Figure 5 are positioned in tubular sections of the collar 26 and operate to collapse and expand the cutters. The springs 32 have one end seated 45 in the bottom of a tubular section of the collar 26 and have their other end positioned against a pad 33 which engages the front side of a plate 35. The plate 35 is secured by means of a bolt 36 to the plunger 18. The springs 34 are fitted also 50 within the ring 26. One end of the springs engages pad 33 which rests against the forward edge of the plate 35 and the other end engages pad 53 which rests against a post 42 which is inserted in the body member 10. A lever 45 is pivoted at 46 55

position to collapse the cutters, said first-mentioned spring being arranged to supplement the reaction of said second spring on said plunger.

7. A collapsible tap comprising a body member, 5 a plunger axially slideable in the body member, radially movable thread cutting elements mounted in the body member and having their inner edges in engagement with beveled portions of the plunger, a latch pivotally mounted on the axis 10 of the body member and having one element adapted to engage a portion of the plunger to lock it in forward or thread cutting position, a collar surrounding the body member having a rack engageable with rack teeth on the said latch for 15 rocking the latch to move it into locking and unlocking engagement with the plunger, means engageable by the work for moving said collar, a spring positioned within the said collar and in operable contact with the said plunger and urging 20 the collar and the plunger in opposite directions, and a second spring in operable engagement with the plunger and with the said body member for retracting the plunger upon release of the plunger by the said latch.
8. A threading device comprising chasers, 25 means mounting said chasers for radial movement, a plunger engaging said chasers to move the same to operative position, latching means for said plunger including an axially movable member and a spring between said member and said plunger, said latching means further comprising a transverse pivot pin disposed in an axial recess in the plunger and a latch member pivoted on said pin and provided with an offset 30 latching portion engaging the plunger adjacent the central axis thereof and means including said axially movable member for operating said latching means to release the plunger and thereby withdraw the chasers to inoperative position.
9. A threading device comprising chasers, 35

means mounting said chasers for radial movement, a plunger engaging said chasers to move the same into operative position, a latch-controlling collar surrounding said plunger provided with a toothed portion and axially movable with respect to the plunger, a latch for the plunger pivoted adjacent the longitudinal axis of said plunger and having a portion engaged by the toothed portion of said collar, a spring between said collar and said plunger and means including said spring for moving the plunger to collapse the chasers to inoperative position upon release of said latch by said collar.

10. A threading device comprising a body member, 15 chasers mounted therein for radial movement, a plunger engaging said chasers to move the same to operative position, a latch-controlling collar surrounding said plunger and axially movable with respect to the plunger, a latch for said plunger and controlled by said collar, a plurality of longitudinal springs disposed in recesses in said collar and arranged to control the movement of said collar and of said plunger when the latter is released by the operation of said latch and another spring disposed in a recess in said 20 collar engaging the body member and plunger and urging the plunger to retracted position to collapse the cutters.

11. A collapsible tap comprising a body member, 25 thread cutting elements supported thereon for radial movement, a plunger for operating said thread cutting elements, latching means for the plunger including a collar slideable on said body member, a spring between the body member and the plunger urging the plunger to collapsing position, and a second spring between the plunger and said collar urging the plunger to collapsing position and the collar to a position where the latching means is operative.
